J. S. CROSSLEY.
ATTACHMENT PLUG.
APPLICATION FILED NOV. 30, 1908.

996,620.

Patented July 4, 1911.

UNITED STATES PATENT OFFICE.

JAMES S. CROSSLEY, OF SOLVAY, NEW YORK, ASSIGNOR TO PASS & SEYMOUR, INC.,
OF SOLVAY, NEW YORK, A CORPORATION OF NEW YORK.

ATTACHMENT-PLUG.

996,620.

Specification of Letters Patent. Patented July 4, 1911.

Application filed November 30, 1908. Serial No. 465,025.

To all whom it may concern:

Be it known that I, JAMES S. CROSSLEY, a citizen of the United States, residing at Solvay, in the county of Onondaga and State of New York, have invented new and useful Improvements in Attachment-Plugs, of which the following is a specification.

This invention relates to contact plugs to be used in electric installations and for electric wiring, and consists in a new construction of plug composed of a part fitted to the socket, a second part carrying the wire terminals, and of spring locking means whereby the two parts may be connected together or disconnected, easily and conveniently without tools or manipulations of special parts and without arranging the one part in any particular relation to the other.

My invention is fully illustrated in the drawing herewith in which the same reference numerals are used in this description to indicate the corresponding parts.

Figure 1 is an elevation of the plug complete. Figs. 2 and 3 are vertical sections substantially at right angles to each other. Fig. 4 is a plan of the bottom or engaging end, of the plug element. Fig. 5 is a plan of the top or engaging end of the cap.

In the figures 1 indicates the base, or plug element, made of any suitable insulating material, preferably porcelain, and provided on its lower, or contact, end with the rim or margin 2 and the recessed post 3, which form the groove, or annular chamber, 4. In said groove is arranged the contact ring, or annular contact, 6 secured in place and electrically connected by the screw or screws 7 to the usual threaded outer plug terminal 8, arranged on the shank 9 of the base. In the recess 11 formed in the post 3, is arranged a spring contact of any suitable shape, by means of which the cup is detachably but firmly connected to the plug member and through which electrical connection is effected between the central or inner socket terminal and one of the conductors. As here shown this spring contact consists of a single piece 14 having two or more somewhat resilient ends 15 provided with the flaring tips 16 and formed with the openings or depressions 17 arranged substantially as shown. This spring contact is held in place by the screw 18, whose head 19 forms the central plug contact. This screw head may be separated and insulated

from the threaded contact by the tip 20 on the porcelain base. The cap 21 is provided with an opening 22 for the easy introduction of the conductor ends, and with depressions, recesses or cavities on its upper or contact surface, preferably as shown, to receive and separate the two wire terminals 23, and 24. The wire terminals having the usual binding screws 25 are secured to the cap respectively by the securing screws 26 and 27, or by other suitable means. Terminal 24 has the stiff metallic shank 28 provided with the head 29, which engages firmly with the spring contact on the base when the cap is set in position and pressed home, and the conductors are thus firmly but detachably secured to the base. The other or outer wire terminal 25 has a claw or clamp 30 secured in place by screw 26 to engage and make contact with the contact ring 6 when the parts are assembled. This clamp is preferably formed with two parts as shown to engage with the ring on both sides; one of said parts, for instance 31, may be made of spring metal, for better electrical connection.

In making my device the plug element may first be screwed into the socket and the cap connected thereto, merely by being pressed home and without any special arrangement of the parts with reference to each other. It is of course understood that the conductors are first connected to the cap by means of the binding screws. Or, if desired, the cap and base may first be connected, and the latter then screwed home into the socket, which may be done without breaking the connection or twisting the wires. In all positions the two parts of the plug are firmly connected and yet may be disconnected easily either by a straight pull or a pull at an angle.

Having thus described my invention, what I claim is,

1. In an electrical attachment plug, the combination with the cap and the base made of porcelain, said base having on its lower surface a central post, a recess in said post, an annular groove around the post and an annular margin extending downwardly beyond the end of the post, of a contact ring in said groove, a spring contact in said recess having opposed spring fingers provided with flaring tips and notches immediately within said tips, a single outer wire termi- 110

nal on the upper surface of the cap having opposed spring fingers to engage the inner and outer surfaces of the ring, a central wire terminal on the cap, and a vertically extending shank on said central terminal having a head adapted to engage with the notched fingers to secure the cap to the base, substantially as described and shown.

2. In an electrical attachment plug, the combination with the cap and the base of insulating material, a contact ring on the base, a terminal on the cap to engage said ring when the parts are assembled, said terminal having opposed spring fingers to engage the inner and outer peripheral surfaces of said ring, a spring contact on the base

having opposed spring fingers provided with flaring tips and notches immediately within said tips, a terminal on the cap oppositely arranged from said first terminal and having an inward extension, and a vertically extending shank on said last terminal to be engaged by the notched fingers to secure the parts when assembled. 20

In testimony whereof I have signed my name to this specification in the presence of two subscribing witnesses.

JAMES S. CROSSLEY.
